UNITED STATES PATENT OFFICE.

JOHN R. ADAMS, OF HOUSTON, AND JOHN J. RYAN, OF SAN ANTONIO,
TEXAS.

AIR-COMPRESSOR FOR DEEP-WELL PUMPS.

SPECIFICATION forming part of Letters Patent No. 367,575, dated August 2, 1887.

Application filed April 27, 1887. Serial No. 236,326. (No model.)

To all whom it may concern:

Be it known that we, JOHN R. ADAMS, of Houston, in the county of Harris, and JOHN J. RYAN, residing at San Antonio, in the county of Bexar and State of Texas, both citizens of the United States, have invented certain new and useful Improvements in Compressors for Pumping or Forcing from Deep Wells; and we do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of a plan view. Fig. 2 is a side elevation. Fig. 3 is an enlarged sectional view of the air-compressor, and Fig. 4 is a detail view of the same.

The invention relates to improvements in air-compressing mechanism for the purpose of pumping or forcing from deep wells and performing similar work; and it consists in the construction and arrangement of a larger and smaller air-cylinder, and the combination therewith of mechanism to force the air from the larger into the smaller cylinder to increase the air-pressure in the latter, as hereinafter described, illustrated in the drawings, and pointed out in the appended claims.

Referring to the drawings by letter, A represents the larger and B the smaller air-cylinder, having preferably one-fourth the diameter of the larger one, but an equal length of stroke.

a is the piston of the former, provided with the inwardly-opening air-valves a', and b is the solid piston of the smaller cylinder, B.

The respective piston-rods C and c of the larger and smaller cylinders are secured to the centers of the cross-heads c' c'', the corresponding ends of which are connected by the parallel rods c' c''. The cross-head c' moves in guideways formed on the bed-frame of the actuating-engine, and the cross-head c'' moves between the arms d of a guide-frame, D, the enlarged inner end of which surrounds the outer end of the smaller cylinder, B, and forms the outer head thereof. The piston and piston-

rods are thus made to move true and together with each other, and the difficulty of keeping packing tight around the pistons under the heavy air-pressure they are subjected to is avoided.

E is the cylinder-head separating the cylinders, and to which the inner end of each is securely attached, and e e' are small chambers in the head E equally distant on each side of its center.

f is an opening from the larger cylinder into the lower part of the chambers e. f' is an opening from the upper part of said chamber into the smaller cylinder, and F is an upwardly-opening valve having a suitable seat between said openings, so that it is evident that when the piston of the larger cylinder moves inward it drives the air within the said cylinder through the said openings and valve into the smaller cylinder, where, as both pistons must move at an equal rate of speed, it is compressed to one-fourth of its bulk and must exercise four times as much pressure to the square inch as in the larger cylinder.

g is an opening from the smaller cylinder into the lower part of the chamber e', and g' a pipe extending from the upper part of said chamber down into a well, or to some other point where compressed air is needed.

G is an upwardly-opening valve having a suitable seat between said opening and pipe, so that when the piston of the smaller cylinder moves inward the compressed air in said cylinder will be driven through the pipe g' to the desired point, and at the same time, the piston of the larger cylinder moving outward, the latter receives a fresh supply of air through its valves a'. The smaller cylinder is surrounded by a chamber, X, filled with water, to cool it when heated by the air being compressed within.

The engine and mechanism to operate the piston and air-compressing apparatus is as follows:

H is the bed-frame of said cylinder, and h the steam-cylinder thereof, having the steam-chest h', provided with the steam and exhaust pipes h² h³, respectively. The piston-rod I of said cylinder rotates, by means of its connecting-rod i and a proper crank or wrist pin se-

cured to the disk j' , the shaft J, The shaft J, by means of the eccentric j , rocker-box j' , connecting-rod j'' , and steam valve-rod j'' , regulates the flow of steam to the cylinder h, while 5 the pump K, that supplies the boiler and the water-chamber X around the smaller air-cylinder, B, has its rod k moved by the cross-head k', to which the steam piston-rod is actuated and which moves on the guides k².

- 10 L is a fly-wheel on the opposite end of the shaft from the disk, which wheel has secured to it a wrist-pin, l, having the outer end of the connecting-rod l' pivoted upon it, the inner end of the said rod being pivoted upon a guide-block, M, moving on the ways m and attached to the cross-head c', which is also directed by the ways m.
- 15 The above is the preferred construction of engine to actuate the air-compressing mechanism; but we do not wish to limit ourselves to this construction, as any other would be effective.

From the above description it is evident that when the engine is in operation the pistons of the larger and smaller air-cylinders will be reciprocated as described, the larger cylinder will at each outward movement of its piston draw in a fresh supply from the open air and at each inward movement will 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

bination of the two air-cylinders of equal length of stroke, but of unequal diameters, and having their inner ends firmly secured to opposite sides of the same cylinder-head, the inwardly-opening valves of the piston of the larger cylinder, and the valves, openings, and chambers in the central common cylinder-head, substantially as described, whereby the larger cylinder is caused to discharge air into the smaller cylinder and the smaller cylinder to discharge compressed air into its discharge-pipe, with the cross-heads on the outer ends of the piston-rods, the parallel rods connecting the corresponding ends of said cross-heads, and the guides to direct the movement of the cross-heads, substantially as specified.

2. In an air-compressing machine, the combination of the actuating-engine constructed substantially as described and provided with the guideways m, of the cylinder A, provided with the piston-rods C and piston a, having the valves a', the cylinder B, having the solid piston b and the piston-rod c, the common cylinder-head, E, having the chambers e e', the valves F and G, and the openings f, f', and g, the discharge-pipe g', the cross-heads c' c'', the rods c' c'', and the guide-frame D, provided with the guide-bars d d, all constructed and arranged substantially as and for the purpose specified.

In testimony whereof we affix our signatures in presence of two witnesses.

JOHN R. ADAMS.
